INVENTOR

UNITED STATES PATENT OFFICE.

EDWARD P. BEACH, OF NEWARK, NEW JERSEY, ASSIGNOR TO UNGER BROTHERS, OF SAME PLACE.

DESIGN FOR A BRACELET, &c.

SPECIFICATION forming part of Design No. 19,715, dated March 25, 1890.

Application filed December 10, 1889. Serial No. 333,286. Term of patent 3½ years.

To all whom it may concern:

Be it known that I, EDWARD P. BEACH, a citizen of the United States, residing at Newark, in the county of Essex and State of New Jersey, have invented and produced a new and original Design for Bracelets and Similar Articles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 In said drawings, Figure 1 represents an edge view of my design for a bracelet or other similar article, and Figs. 2 and 3 are plan or face views of the same in different degrees of enlargement.

20 Similar letters of reference indicate like parts where they occur.

The three views are deemed sufficient to fully illustrate my design, the leading feature

of which consists in the peculiar configuration presented in the surface of the bracelet 25 or other article, as will be hereinafter set forth and claimed.

Referring to said drawings, *a* and *b* indicate two wire-like parts, each formed into or presenting in heavy lines a series of curves 30 along the outer edges and convolutions of an ovate shape through the center, said curves and convolutions intersecting with and lapsing upon one another, as will be seen and understood upon reference to Fig. 2. 35

What I claim is—

The design for a bracelet or similar article herein shown and described.

In testimony that I claim the foregoing I have hereunto set my hand this 4th day of 40 December, 1889.

EDWARD P. BEACH.
